UNITED STATES PATENT OFFICE.

ROBERT LEWIS, OF BRIDESBURG, PENNSYLVANIA.

DESIGN FOR WOVEN FABRIC.

SPECIFICATION forming part of Design No. 26,502, dated January 5, 1897.

Application filed December 2, 1896. Serial No. 614,246. Term of patent 3½ years.

To all whom it may concern:

Be it known that I, ROBERT LEWIS, a citizen of the United States, residing at Bridesburg, in the county of Philadelphia and State of Pennsylvania, have invented and produced a new and original Design for Woven Fabrics, of which the following is a specification, reference being had to the accompanying line drawing, making a part of the same, and which is sufficient to enable others skilled to make and use my invention.

The drawing shows only one-fourth of the

design. The three-fourths not shown is substantially like the one-fourth that is shown. Having, as above, fully described my invention, what I claim as new, and desire to secure by Letters Patent, is—

The design for a woven fabric, as shown and described.

ROBERT LEWIS.
